Primary Examiner — Lucy Lieberman(74) *Attorney, Agent, or Firm* — Donald J. Ranft; Collen IP(57) **CLAIM**

The ornamental design for a watch, as shown and described.

DESCRIPTION

FIG. 1 is a front right perspective view of a watch showing our new design;

FIG. 2 is a front left perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and,

FIG. 9 is a rear perspective view thereof.

The portions of the watch shown in broken lines form no part of the claimed design.
